UNITED STATES PATENT OFFICE.

FERDINAND STRAUSS, OF NEW YORK, N. Y.

DESIGN FOR A MINIATURE RAILWAY TOY.

Application filed October 22, 1924. Serial No. 11,148. Term of patent 7 years.

To all whom it may concern:

Be it known that I, FERDINAND STRAUSS, a citizen of the United States of America, residing at New York city, county and State of New York, have invented a new, original, and ornamental Design for a Miniature Railway Toy, of which the following is a specification, reference being had to the accompanying drawing, forming part thereof, which illustrates a perspective view of a miniature railway toy showing my new design.

I claim:—

The ornamental design for a miniature railway toy, as shown.

Signed at New York city, N. Y., this 10th day of October, 1924.

FERDINAND STRAUSS.
